UNITED STATES PATENT OFFICE.

ADAM CRUICKSHANK, OF CHICAGO, ILLINOIS.

DOG-HOUSE FOR OPEN-HEARTH FURNACES.

No. 888,962.

Specification of Letters Patent.

Patented May 26, 1908.

Application filed July 10, 1907. Serial No. 383,033.

To all whom it may concern:

Be it known that I, ADAM CRUICKSHANK, a citizen of the United States, residing at Chicago, in the county of Cook and State of Illinois, have invented certain new and useful Improvements in Dog-Houses for Open-Hearth Furnaces, of which the following is a specification.

My invention relates to open hearth furnaces and particularly contemplates the provision of a dog-house built therein for the protection of the oil burners and the brick work thereabout.

My invention further and specifically resides in the following features of construction, arrangement and operation as will be hereinafter described with reference to the accompanying drawings, in which

Figure 1 is a vertical sectional view through the forward portion of an open hearth furnace illustrating my improvements attached thereto, and Fig. 2 is a view, half front elevation and half transverse section of the furnace and its improvements shown in Fig. 1.

In the accompanying drawings A represents an open hearth furnace comprising in its construction a front wall B and the surrounding walls closing combustion chamber C. The oil pipe D is, as usual, arranged through the front wall B and combustion chamber C and provided with a regulating valve E.

A small opening is usually made through the wall B through which the pipe D projects within the combustion chamber C. This construction however, necessitates a great amount of expense and work for the reason that the heat quickly burns out the pipe D and that portion of the wall B which surrounds the same. To obviate this expense I provide the wall B with a comparatively large opening 1 strengthened by an arch 2 thereabove and having walls 3 extending rearwardly within the combustion chamber C. At the end of the walls 3 is arranged a downwardly slanting baffle wall 4 partially closing the chamber 5 formed by the walls 3 and providing a reduced opening 6 for

the entrance pipe or pipes D. It will thus be seen that the chamber 5 is protected from 50 the direct heat from the combustion chamber C by means of the baffle wall 4, while said chamber 5 will on the other hand have direct communication with the atmosphere through the opening 1 in the furnace wall B, becoming thereby an air chamber for maintaining 55 a low temperature in the pipes D and preventing the heat of the combustion chamber burning out the same and the surrounding walls, it being of course understood that this 60 dog-house construction comprising walls 3 and 4 and the surrounding parts will be entirely of fire brick construction.

Having thus fully described my invention, I claim:

1. The combination with a furnace and its inwardly extending fluid pipes, of a dog-house built through the wall of said furnace and comprising inwardly extending walls forming an air chamber within the same 70 through which said pipes are arranged, and a wall at the inner end of said dog-house partially closing said chamber to protect the same from the heat within said furnace, substantially as described.

2. The combination with an open hearth furnace and its inwardly extending fluid pipes, of a dog-house built through the wall of said furnace and comprising inwardly extending walls forming an air chamber within 75 the same having direct communication with the atmosphere, and a baffle wall slantingly arranged at the inner end of said dog-house, and partially closing said air chamber to protect the same from the heat within said 80 furnace, said baffle wall forming beneath the same an opening for the passage of said pipes through said dog-house within the furnace, substantially as described.

In testimony whereof I affix my signature 85 in presence of two witnesses.

ADAM CRUICKSHANK.
